2,300,550

MEANS FOR PREPARING PRINTING PLATES
FOR APPLICATION TO PRINTING CYLINDERSWilliam F. Huck, Richmond Hill, N. Y., assignor
to R. Hoe & Co., Inc., New York, N. Y., a corpora-
tion of New YorkOriginal application September 2, 1936, Serial No.
99,113. Divided and this application March 7,
1940, Serial No. 322,670

2 Claims. (Cl. 29—89)

The invention disclosed in this application, which is a division of the application that resulted in Patent No. 2,234,170, relates to method and means for preparing printing plates for application to printing cylinders and more particularly to preparing plates for use in rotary lithographic and photogravure printing machines. The plates used in such types of printing machines are in many instances formed of flexible sheet metal upon a surface of which the design to be printed is produced by well known methods. These plates are wrapped about the printing cylinder, being secured in place by means of suitable devices.

In the use of this invention, plate clamping bars at each end of the plate are located a predetermined distance from the printing form or design on the plate. The fixture shown in the accompanying drawings and as hereinafter described is particularly useful in the accomplishment of the above desideratum.

One of the objects of this invention is to provide a fixture having means to qualify the length of printing plates plus their clamping bars, for convenient application to the cylinders of a printing machine.

Still another object is to provide a method of securing accuracy in the register of lithographic printing plates without interfering with the operation of the press.

It is also an object of this invention to provide a printing plate registering fixture of generally improved construction, whereby the device will be simple, durable and inexpensive in construction, as well as convenient, practical, serviceable and efficient in its use.

With the foregoing and other objects in view, which will appear as the description proceeds, the invention resides in the method and the combination and arrangement of parts, and in the details of construction and in the method of operation hereinafter described and claimed.

The preferred embodiment of the invention is illustrated in the accompanying drawings, wherein:

Figure 1 is a side elevational view of a plate registering fixture embodying the features of this invention;

Figure 2 is a partial plan view of the fixture shown in Figure 1, looking in the direction of arrow 2;

Figure 3 is a section on line 3 of Figure 2, showing the plate clamp in unclamped position;

Figure 4 is a view similar to Figure 3, but showing the parts in another position whereby

the plate is clamped and a bending operation claimed in Patent No. 2,234,170 is about to be started;

Figure 5 is another view similar to Figure 3, but showing the position of the parts directly after a plate end has been bent;

Figure 6 is still another view similar to Figure 3, and showing the position of the parts after bending and unclamping of the plate, and showing the stripping of the plate from the fixture;

Figure 7 is a partial plan view of a part of the fixture looking in the direction of arrow 7 in Figure 1; and

Figure 8 is a sectional view of the parts shown in Figure 7 looking in the direction of arrow 8 thereon.

The fixture selected to illustrate the features of this invention is particularly designed for the purpose of preparing a printing plate 11 formed of flexible sheet metal and having a clamping bar secured to each of its ends, which bar comprises a lower member 12 and an upper member 13 which are secured together by screws 14 whereby the respective plate end is clamped therebetween. As referred to above, the plate 11 is intended to be wrapped about a printing cylinder and retained thereon by suitable devices which use the clamping bars at each end thereof to assist them in so doing. Inasmuch as the clamping bars are used by the aforesaid devices, it is necessary to locate the bars relatively to the printing form or design on the plate in order that the matter printed therefrom will be properly located upon the sheet being printed.

The fixture of this invention is provided with a table-like plate support 15. The plate support 15 may be constructed of wooden strips 16 mounted upon a frame 17 of metal plates, which is supported above the floor by a frame 18 carried by a standard 19. The fixtures are provided with a plate bending device at each end of the table 15, which is used chiefly when plates are prepared for mounting on the cylinders of printing machines that print from a web, wherein a cut-away portion of the periphery of the cylinder in which the clamping devices are mounted, is relatively small, and it is necessary to bend the plates quite sharply so that the clamping bars may be fitted into the restricted space. The invention, with the inclusion of the bending device, forms the subject of the hereinbefore mentioned patent. The bending devices at each end of the table are the same in structure and operate similarly on the plate, in view of which only one will be described.

A bearing bracket 21 is secured at each side of each end of the table 15 by bolts 22 and supports a bearing bushing 23, which is eccentrically mounted therein and is secured thereto by screws 24 passing through elongated slots 25 formed in a flange 26 formed as a part of the bushing 23. An angle bar 27 having flanges 28 and 29 (Figure 2), substantially at right angles to each other, is disposed between each pair of brackets 21 at each end of the table 15 with gudgeons 31 extending from each end of the bar 27 journaled in the respective bearing bushing 23. An operating handle 32 extends from the bar 27 and is provided for the purpose of rocking the bar upon its gudgeons 31. Cooperating spring fingers 33 secured to the underside of the table 15 cooperate to grip the handle 32 and retain it in inoperative position. In its inoperative position the flange 28 is disposed in a horizontal plane with its operable surface in alignment with the upper surface of the table 15, and the flange 29 is vertically disposed. A stop member 34 disposed between the fingers 33 is adapted to positively insure such position of the flanges 28 and 29 due to the engagement of the handle 32 therewith.

The flange 28 is provided with a groove 35 which extends the length of the flange and is of proper width and depth to receive the lower member 12 of the plate clamping bar. In cooperation with the groove 35 in the flange 28 at the other end of the table 15, the plate 11 with its clamping bars may be qualified as to length by the disposal of a clamping bar in each groove 35 and adjusting the clamped plate between the members 12 and 13 thereof. Adjustment of the eccentric bearing bushing 23 permits slight changes in the distance between the grooves 35 to obtain correct measurements and location of the plate 11.

A gauge blade 36 is pivotally mounted in a bracket 37, which is slidably mounted upon the frame 17 at one end of the table, and is provided for the purpose of gauging the distance between the printing design on the plate 11 and the plate clamping bar. A blade 36 is disposed at each side of the table 15 whereby the printing design may be squared with the edge of the frame 17 and disposed parallel with the plate clamping bar. Each of the brackets 37 may be secured in place on the frame 17 by means of a clamping set screw 38, thus permitting the operation of the fixture upon a plurality of similar plates and insuring the same dimensions in the location of the printing design relatively to the clamping bar on each.

A pair of arms 41 and 42 that are used chiefly in connection with plates for web printing machines, are swingably mounted upon each of the gudgeons of each of the angle bars 27. Extending between the arms 41 and 42 of each pair is a clamping member 43 which is secured to the arms and is swingable therewith by means of a handle 44 secured to the member 43 by screws 45. The member 43 has a plate engaging surface 46 which, in this instance, is preferably covered by a sheet of soft felt 47 clamped to the member 43 by securing bars 48 and 49 and screws 51. Posts 52, extending upwardly from each bracket 21, have upon their upper ends a swingable lever 53 (Figure 2) pivoted to the respective post by a screw 54. One end of each of the levers 53 is provided with a camming surface 55 adapted to engage a camming surface 56 (Figure 4) formed on the upper surface of each of the arms 41 and 42 when the member 43 is in engagement with a plate 11 on the table 15 to securely clamp the

plate between the same. The other end of each of the levers 53 is extended to provide an operating handle 57 therefor.

A bar of metal forming a bending head 58 (Figure 5) also used chiefly in connection with web printing machines, is disposed on edge against the surface of the flange 29 of the angle bar 27 and secured thereto by screws 59 which pass through elongated openings 61 in the flange 29 and thread into the edge of the head 58 abutting the flange. The other edge 62 of the head 58 is rounded over and cooperates with the edge of a swingable plate stripping bar 63 provided at and extending across the end of the table 15 to bend the plate 11. The head 58 extends along the flange 29 substantially its entire length. Alignment of the head 58 on the flange 29 permitted by the elongated openings 61 and of the eccentric bushing 23 in which the gudgeons 31 are journaled compensates for variations in thickness of the plate 11 and permits correct alignment of the rounded edge 62 of the head 58, with the plate stripping bar 63. While the angle bar 27 is being swung to bend a plate by means of the operating handle 32 the plate clamping bar 12, 13 is released from the groove 35 in the flange 28.

The plate stripping bar 63 is provided with gudgeons 64, one at each end, which is journaled in the adjacent bracket 21. An operating handle 65 (Figure 6) is secured to the bar 63 by screws 66 and extends downwardly and outwardly into convenient reach of the operator. The bar 63 is operated after a plate 11 has been bent to raise the bent end of the plate to readily permit its removal from the fixture.

By the use of a fixture as described above, a plate 11 having a printing design thereon, may be located in respect to its end clamping bars 12, 13, due to the gauge blades 36 and the grooves 35 in the flange 28 of the angle bar 27 to be parallel therewith and with the bars 12, 13 square with the side edges of the plate.

The mechanism disclosed herein and also in Patent No. 2,234,170 is adapted to the preparation and registration of plates for web printing machines, in which the gap in the plate cylinder for accommodation of the plate holding devices is very narrow, and in consequence it is necessary to make a sharp bend in each end of the plate in order that the clamping bars may be secured inside of the cylinder.

The operations performed during the use of this fixture when the bending device is not used, comprise the placement of clamping bars 12, 13 in the grooves 35, the placement of a plate 11 on the table 15 (Figure 3), and by the use of the gauge blade 36, so locating the plate on the table, that the clamping bars may be secured at a desired fixed distance from the printing form on the plate.

It will be observed that the accuracy with which the clamping bars are thus positioned with respect to each other and with respect to the printing form, allows plates to be so accurately registered that they can be placed upon their printing cylinders with the accuracy required for high grade printing, and without the necessity for subsequent adjustment.

It will be understood that the invention may be embodied in other specific forms without departing from the spirit or essential attributes thereof, and it is therefore desired that the present embodiment be considered in all respects as illustrative and not restrictive, and it will be further understood that each and every novel

feature and combination present in or possessed by the mechanism herein disclosed forms a part of the invention included in this application.

What I claim is:

1. A fixture for use in assembling clamping bars on the edges of printing plates having printing forms thereon wherein it is desired to accurately locate the bars on the plates with respect to the printing forms, said fixture comprising a support, said support having a flat top of sufficient size to support a printing plate in flat condition and allow for adjustment thereof on said top, the plate being supported with its printing form side up, a locator, means whereby said locator may be fixedly related to the flat top and overlie the printing form on a printing plate, so that a printing form may be located by said locator for accurately positioning a plate on said top, and said support including a transverse recess extending across one end thereof and of sufficient depth to receive and hold a bar with its entire plate clamping surface flush with said flat top, the recess being in fixed relation to said flat top so that when a plate is located by said locator it has its printing form in fixed relation to said locator and likewise with relation to said bar recess, whereby a bar may be affixed to the plate in accurate relation to its printing form.

2. A fixture for use in assembling clamping bars on the edges of printing plates having printing forms thereon wherein it is desired to accurately locate the bars on the plates with respect to the printing forms, said fixture comprising a support, said support having a flat top of sufficient size to support a printing plate in flat condition and allow for adjustment thereof on said top, the plate being supported with its printing form side up, a locator, means whereby said locator may be fixedly related to the flat top and overlie the printing forms on a printing plate, so that a printing form may be located by said locator for accurately positioning a plate on said top, and said support including a transverse recess extending across each end thereof and each recess being of sufficient depth to receive and hold a bar with its entire plate clamping surface flush with said flat top, each recess being in fixed relation to said flat top so that when a plate is located by said locator it has its printing form in fixed relation to said locator and likewise with relation to said bar recesses, whereby a bar may be affixed to the plate in accurate relation to its printing form.

WILLIAM F. HUCK.
